UNITED STATES PATENT OFFICE

KARL SCHMIDT, OF NEURUPPIN, GERMANY

PORTABLE FIRE EXTINGUISHER

Application filed August 3, 1927, Serial No. 210,358, and in Germany August 7, 1926.

The invention relates to portable fire extinguishers and more particularly to the accommodation of cartridges or bottles containing liquid gases, such as carbonic acid, in fire extinguishers, as well as to a device for holding and opening such cartridges or bottles.

If cartridges or shells containing liquid gases are inserted into fire extinguishers with a striking pin or other opening device directed upwards, gas escapes from the opened bottle for a short time only, because the outlet opening of the bottle freezes up. This freezing up takes place for the reason that the expanding gas is not able to withdraw the necessary heat of evaporation from the air surrounding the cartridge present in the air space of the extinguisher.

I avoid this drawback by inserting the cartridge or bottle into the extinguisher with the outlet opening directed downwards and immersed in the extinguishing liquid stored in the apparatus. In this way the liquefied gas contained in the cartridge or bottle is obliged to pass into the extinguishing liquid in the liquid state. The extinguishing liquid protects the cartridge against freezing and supplies the necessary heat of evaporation and the extinguishing liquid itself is cooled in consequence of this withdrawal of heat which has a favourable effect upon the extinguishing qualities of the liquid.

According to my invention the cartridge or bottle is not accommodated in a basket within the extinguisher as customary with acid bottles and gas developing cartridges, but is suspended upside down from a rod which is passed outside through an airtight packing. This rod serves at the same time to push the cartridge against the bottom of the extinguisher so that a pin or the like is forced into the bottle and its outlet opened. The rod carrying the cartridge or bottle is preferably made in two parts so that on the lower end of its upper portion guided in the stuffing box a striking plate may be fixed when it is desired to use this portion as striking pin in the ordinary way when the extinguisher is to be equipped with an acid bottle or a gas developing cartridge instead of a cartridge containing liquid gas.

An embodiment of the invention is illustrated by way of example in the accompanying drawing.

The single figure of the drawing shows a longitudinal section through the improved extinguisher.

Referring to the drawing *a* is the shell of the extinguisher filled with the extinguishing liquid to approximately the level *n*, *b* the squirming nozzle and *c* the cover closing the charge opening in the top of the extinguisher and in which the striking pin *d* is guided in the customary manner by a stuffing box, *m*. The ordinary blow transmitting plate of this striking pin is unscrewed and in its place an extension rod *e* is screwed into the striking pin. Upon the free end of this extension rod provided with screw thread is screwed a cup-shaped holder *f* with internal screw thread into which is in turn screwed the bottom portion of the cartridge *g*. The length of the rod *e* is such that the pin or the like *h* for opening the outlet of the cartridge is situated near the dome-shaped bottom *i* of the extinguisher shell or casing. By a blow upon the plate *k* the cartridge is driven towards the bottom *i*, its opening pin *h* comes in contact with the bottom and is forced into the neck of the cartridge or bottle whereby the latter is opened.

Various changes and modifications may be made without departing from the spirit of my invention and I desire therefore, that only such limitations be placed on my claims as are imposed by the prior art.

I claim as my invention:—

1. In a portable liquid fire extinguisher, a container for the squirming liquid provided with a charge opening in the top and a squirming nozzle, a cover for closing said opening, a stuffing box in said cover, a rod passing through said stuffing box and adapted to be axially displaced from outside, a cartridge containing liquid gas and provided with a striking pin suspended from the inner end of said rod so that said pin is located near the bottom of said container.

2. In a portable liquid fire extinguisher a container for the squirming liquid provided with a squirming nozzle and a charge opening

in the top, a cover for closing said opening, a rod passing tightly through said cover and adapted to be axially displaced from outside, an extension rod screwed on the inner end of
5 said first rod and provided with a cup-shaped lower end, and a liquid gas containing cartridge provided with a striking pin adapted to be screwed with its bottom into said cup-shaped end of the extension rod so that said
10 striking pin is located near the dome-shaped bottom of said container.

I affix my signature.

KARL SCHMIDT.
